UNITED STATES PATENT OFFICE

WILLIAM J. BYRNES, OF HUBBARD WOODS, RICHARD A. BYRNES, OF CHICAGO, AND CLYDE J. SAUNDERS, OF ELGIN, ILLINOIS; SAID SAUNDERS ASSIGNOR TO SAID WILLIAM J. BYRNES AND SAID RICHARD A. BYRNES.

NEWS STAND STRUCTURE

Application filed May 28, 1928. Serial No. 281,298.

Our invention relates to a news stand structure which has to do especially with a structure of this character and may be readily installed on street corners and in other places where ground space must be conserved, and which is adapted for the storage and sale of newspapers, magazines, confections, and the like.

One of the objects of our invention is to provide a novel, compact and light weight structure of the foregoing character which is exceedingly simple in construction, cheap to manufacture, strong and durable and which is capable of being moved bodily from place to place if, and as, the circumstances require it.

Another object is to provide a news stand structure which is adapted to carry advertising, descriptive, and other similar, matter in a highly conspicuous manner for the information of the purchaser, as well as the public generally, the arrangement being such that various forms of advertising and descriptive matter may be substituted from time to time if that is found desirable. Thus, our invention may greatly increase the income of the stand owner by keeping the public fully informed as to the merchandise for sale and by renting advertising space on the stand.

It is well known that the attendants of news stands which may be stationed on street corners, and other similarly exposed places, suffer great discomfort from the weather (rain, snow, wind, etc.) and at times considerable loss is experienced by the papers, etc., getting wet from rain or snow and by the papers being blown about by strong winds. A further object of our invention is to provide an adjustable stand structure which is adapted to protect both the contents of the stand and its attendant from all kinds of weather, such structure also being adapted to overcome all other objectionable features of prior stands of this character.

Still another object is to provide adjustable weight means for securely anchoring the papers in place in the stand compartment, such means not interfering with the ready removal of the papers when sales are

made. The weight means which we employ is also adapted to receive and hold the money received in the sale of the papers.

A further object is to provide a stand requiring only a very small ground supporting surface and which has merchandise-dispensing and storage compartments arranged to support a large quantity of papers, magazines, etc. We also provide adjustable means for increasing the size of the merchandise-dispensing compartment including extensible side, top and bottom walls, certain of said walls being so arranged that they may be folded to close the stand compartments.

Other objects and advantages have to do with various novel details and arrangements of parts, including the forming of the various parts from sheet metal, the manner of supporting certain of the adjustable walls for sliding and swinging movements, the manner of supporting and anchoring the top structure to the side walls, the manner of anchoring the stand as a whole to a supporting part, and the manner of arranging the various wall parts to provide a compact structure, all of which contribute to the efficiency, durability and cheapness of our structure as well as the accomplishing of the objects mentioned hereinabove.

Additional objects and advantages will become apparent as this description progresses, and by reference to the drawings, wherein,—

Figure 1 is a perspective view of one form of stand structure embodying our invention and showing the compartments of the same closed;

Fig. 2 is an enlarged perspective view of the stand of Fig. 1 and showing the same with its compartments open;

Fig. 3 is a separated perspective view of one of the adjustable side walls of the stand;

Fig. 4 is an enlarged transverse vertical section of the stand with the parts shown in substantially the same position as they appear in Fig. 2;

Fig. 5 is a horizontal section taken substantially on line 5—5 of Fig. 4;

Fig. 6 is a separated perspective view of the under side of one of the compartment shelves;

Fig. 7 is a detail section through an upper corner of the stand as at line 7—7 of Fig. 4;

Fig. 8 is a vertical section taken substantially on line 8—8 of Fig. 4;

5 Fig. 9 is a side elevation of the stand, showing advertising and descriptive matter supported thereon; and

10 Fig. 10 is a detail section taken substantially on line 10—10 of Fig. 8 and showing the manner of supporting the advertising, etc., matter.

We preferably form our stand from sheet metal, but it is to be understood that other materials may be used, if found desirable, 15 without departing from our invention. In the form which we have chosen to illustrate our invention, we employ an outer rectangularly-shaped shell structure formed from a single sheet of metal to provide side walls 10 20 and back wall 11. The bottom edges of these walls are turned outwardly to provide horizontal bottom flanges 10^a and 11^a which are adapted to be secured to a suitable support for anchoring the stand in place. The support (not shown) may be a street or sidewalk surface, or it may be a supporting standard of some suitable form which is, in turn anchored to the street or sidewalk surface. The lower vertical edges of the walls 10 and 11 25 support a raised bottom 12 (Figs. 2, 4 and 7) having a rear depending flange 12^a secured to the rear wall 11 and side depending flanges 12^b secured to the side walls 10. This bottom is also provided with a downwardly extending front flange 12^c (Fig. 2) having its lower edge extended outwardly at substantially right angles to provide a horizontal flange 12^d similar to the wall supporting flanges 10^a and 11^a and which serves a purpose similar 30 to that of the latter mentioned flanges.

The upper front edge surface of the side walls 11 is flanged inwardly as at 13 (Fig. 4) and an upper front wall surface 14 is attached to these flanges 13 in any suitable manner to provide a permanently closed top shell part. The upper edges of the front, side and rear walls are flanged outwardly as at 15 and then vertically upward at 15^a to provide a support for the top 16 overhanging the side, front and rear walls. More particularly, the top, preferably, takes a polygonal and upwardly tapering shape with each of its sections 16^a of substantially V-shape and having an angular disposed flange 16^b fitting over 45 and joined to the vertical flange 15^a of the side, front and rear walls (Fig. 4). In this manner, an overhanging roof structure is provided which presents a very neat appearance and which also tends to direct water 50 which may fall therefrom outwardly beyond the lower wall surfaces.

The interior of the shell structure is divided into upper and lower compartments 17 and 17'. The upper compartment 17 preferably contains a supply of articles for imme-

diate sale, while the lower compartment 17' is preferably used for storage purposes. These compartments are formed by a horizontal partition member 18 which is provided with side and rear edge flanges 18^a and 18^b adapted to be secured to the adjacent shell wall surfaces in any desired manner and, approximately, at the point indicated in Figs. 2, 4 and 7. The front edge of this partition 18 is also turned downwardly and then inwardly upon itself at 18^c for a purpose which will become obvious hereinafter.

The upper compartment 17 is provided with shelves 19 and 20, and it is adapted to be closed at its front by a swingably and horizontally adjustable front wall or cover 21 when the stand is not in use. Adjustable side walls 22 are also associated with the upper compartment 17 for extending its sides to protect the contents of the stand and the attendant from the weather when necessary. More specifically, the upper compartment is provided with inner side walls 23 parallel with but spaced from the outer side or shell walls 10 to provide therebetween a space 80 adapted to slidably receive the adjustable side wall 22 permitting such wall to be moved outwardly beyond the front edges of the adjacent walls to varying extents as indicated in Figs. 2 and 4. The bottom edges of the inner side walls 23 may be secured to the partition member 18 in any desired manner, and its upper edge, adjacent the lower edge of the front wall 14, is turned outwardly then upwardly and then inwardly to form a slide-groove 24 which is of a depth substantially equal to the width of the space between the inner and outer walls 10 and 23 thus serving as a means for spacing these walls apart. This grooved surface may be secured to the outer wall 11 in any desired manner.

The adjustable front wall 21 or cover is arranged for hinging movements when in one position and for sliding movement in the grooves 24 when it is opened and moved to a substantially horizontal position about its supporting hinge. More particularly the cover 21 has its upper end intermediate its side edges curved downwardly and inwardly as at 21^a to provide an open-sided hinge element. A rod 25 is supported by the side walls 10 in line with the forward open edges of the grooves 24 and this rod is embraced by the wall hinge element 21^a to provide for its swinging movements. With this construction, when the cover wall is moved to a substantially horizontal position about the hinge rod 25, it may then be slid inwardly away from the rod 25 (the open side of the wall hinge element 21^a permitting this) with its side edges riding in said inner wall grooves (Figs. 2 and 7). Also, when this cover is to be moved to its closed position, it may be slid bodily outward to engage the rod 25 and cover hinge element 21^a, 130

as above described, and it may then be swung downwardly to its closed position (Fig. 1). The cover, in its horizontal position serves as an adjustable top compartment wall which 5 projects forwardly to shelter the contents of the compartment 16, as well as the attendant standing therebeneath from the sun, rain, etc.

The compartment shelves 19 and 20 are supported by the inner compartment walls 10 23 as follows: Vertically spaced inwardly projecting flanges 26 are struck out from the inner walls 23 providing aligned horizontal supports for the shelves as is obvious from Figs. 4 and 8. The shelves at their rear corners have downwardly projecting extensions 15 or lugs 27 which are adapted to extend downward behind the shelf supports 26, when the shelves are in position, to prevent horizontal displacement of the shelves when articles 20 are removed therefrom. This arrangement also permits ready removal of the shelves by first moving the same vertically to disengage the projections 27. In the drawings, I have shown the upper shelf 19 of lesser 25 depth than the lower one for more conveniently displaying the articles carried thereby, but I do not desire to be limited to this particular arrangement since it is obvious that the sizes of the shelves, as well as other 30 of the parts of the stand, may be varied without departing from our invention.

We find that it is highly desirable that the extensible side walls 22 be anchored in such a way that they may not be removed entirely 35 by outward sliding movement and so that they will not bind during their sliding movements. To this end, we utilize the openings 28 formed in the inner compartment walls 23 when the shelf supports 26 are struck 40 therefrom. Spaced tongues 29 are struck from the inner wall surface of the extensible side walls 22 at such a point that they will extend into and ride freely through the openings 28. In this manner, it is obvious that 45 the extensible walls 22 are guidingly supported for free sliding movement without tipping, such as would cause binding and, at the same time, definite stops are provided for limiting their outward sliding movement. The extensible side walls are each provided 50 at their front edges with inturned flaps or handles 30 which may be readily grasped for extending the walls 22 and for moving the same inwardly.

We also desire to use the upper part of the stand above the compartment 16 for storage 55 purposes, whenever that is found necessary or desirable. To this end, we mount a shelf 31 immediately above the compartment 16. The opposite ends of this shelf 31 are, preferably, supported by the upper surfaces of the inner side wall groove portions 24. Thus, when the cover 21 is swung upwardly to an 60 open position, and before it is slid inwardly to the position shown in Fig. 4, articles may

be placed upon or removed from the shelf 31.

The bottom compartment 17' is adapted to be closed by a separate cover 32 which is adjustably mounted similarly to the cover 21. To provide for this, we mount a channel-guide support 33 upon the opposite side walls 11 immediately beneath the partition 18, providing grooved surfaces similarly to the upper groove surfaces 24 in the upper compartment 16. A hinge rod 34 is mounted at the front or open edge of the guide grooves 33 and this rod is adapted to be embraced by an upper curved end hinge portion 35 of the cover 32 similarly to the cover 21, so that when the cover 32 is swung upwardly to a substantially horizontal position it may be moved inwardly to disengage the same from the hinge rod 34 and to engage its side edges with the guide grooves 33. Conversely, when this cover is slid outwardly the 70 rod 34 will again be engaged and the cover 75 may be swung downwardly to its closed position (Fig. 1). The channel support 33 obviously will hold the lower cover 32 in various horizontal positions, and it may thus 80 serve as an extension for the partition member 18, giving a larger surface for supporting additional papers, magazines, etc. This 85 cover 32 may well be used for the purpose just described during rush hours when a 90 large number of the same or different kinds of papers may be handled.

We have found it very convenient to carry the newspapers in the bottom part of the compartment 17 upon the partition member 100 18 and to carry magazines, confections, etc., upon the shelves 19 and 20. In some instances, it may be desirable to anchor the papers (such as indicated at A in Fig. 2) 105 firmly in place. To accomplish this, we provide adjustable weights 36 supported by horizontal arms 37 having a vertical extension 38 swingingly and reciprocatably supported by spaced bearing straps 39 struck out from the inner compartment wall 23 (Fig. 2). 110 This arrangement permits the weight member 36 to press downwardly upon the papers, at the same time permitting such member to be raised and swung away from the papers for the addition of papers to the stack A or 115 the removal of the stack itself. For the further convenience of the attendant, the weights 36 are cup-shaped so as to receive and hold money received in the making of sales. This greatly facilitates the work of 120 the attendant during rush hours.

There will, of course, be times when the stand is not in use and at which times it is desired to close and lock the same without rearranging or otherwise disturbing the contents thereof. To this end, we provide a locking tongue 40 which has its inner end fastened as at 40^a to the partition member 18 with its forward end projecting through a slot 40^b in the front edge flange 18^c of the 125 stand. The outer end of the tongue 40 is 130

member 18. In this manner, the tongue is rigidly supported in position to enter the slot 41 in the lower edge of the cover 21 when that cover is moved to its closed position. 5 As indicated in Fig. 1, a lock 42 may then be inserted in the opening 43 in the projecting part of the tongue to lock the cover in this position. A similar arrangement is provided for the lower cover 32. In this case, 10 the locking tongue 44 is supported by the bottom 12 with its forward end projecting through a slot in the front vertical flange 12^a of this bottom. The bottom cover is provided with a slot 45 which receives the projecting end of the tongue 44 to which the lock 46 is attached in the manner indicated in Fig. 1.

Our stand, when installed on a street corner, obviously will be very conspicuous. 20 Therefore, to increase the income of the stand owner to a considerable extent, we so arrange our stand that it may carry advertising matter on all sides (and the top if found desirable), the spaces for such advertising matter being rented to those who wish to advertise. The front surfaces of the compartment covers may have advertising or the descriptive matter permanently placed thereon, such matter being observable only when 25 the covers are closed. This may also (but not necessarily so) be true of the front wall surface 14 and the top surfaces 15. However, we preferably so arrange certain of the wall surfaces that advertising cards, panels, and the like, may be mounted thereon in such a way that new advertising matter may be substituted and displayed from time to time. In the drawings, we have shown such an arrangement applied to the side wall surfaces only (Fig. 9), but it is to be understood 30 that it may be equally well applied to the back wall surface 11 and the stationary front wall surface 14. In carrying out this feature of our invention, we provide at the desired points along the side walls pairs of spaced channel members 47 which are secured to the side wall surface in any desired manner (Fig. 9). The open channel surfaces of these members 47 are directed toward 35 each other so as to slidably receive and retain advertising cards or panels 48. The same form of guide-supporting members may be mounted on the back wall 11. It will be obvious that with this arrangement new cards or panels 48 may be substituted from time to time bearing the same or different subject matter. One or more of these spaces may be rented to an advertiser, thus providing a very substantial income from this standpoint. 40 Some of the matter contained on the outer part of the stand may be advertising and descriptive matter relating to the goods sold at the stand, while the other matter relates to miscellaneous goods.

45 We believe that the manner of setting up

and operating our stand will be obvious from the foregoing. It will be very clear that the various detail parts have been so formed and are so associated with each other that the stand as a whole may be constructed very cheaply, at the same time providing a stand which is exceedingly strong and durable. The structure as a whole is very compact, at the same time providing for the storage and dispensing of a large number of articles of the same or different kinds. The articles contained therein are at all times protected from the weather, the means affording such protection being capable of rapid and easy adjustment as the conditions require.

50 It is to be understood that while we have shown only one form of structure embodying our invention, various changes in details and the arrangements of parts thereof may be made without departing from the spirit and scope of our invention as defined by the claims which follow.

55 We claim:

1. In a news stand, means including spaced side walls for forming a compartment with an opening at its front, a cover member for said opening, means for supporting said cover member so that it is movable to horizontal and vertical positions and adapting said cover member to close said front opening in its vertical position and to serve as an adjustable top covering in its horizontal position, and members securely interlocked with and slidably supported by said side walls so as to be extensible to extend the side edges of said opening and serving with said cover to provide a weather-protected extension for said compartment.

2. In a news stand, means forming a compartment with an opening at its front, a cover for said opening which is swingable in one position to close said opening and is slidably in another position along the upper edge of said opening toward and from its swingable position and including a supported position wherein it extends out beyond said opening to shelter the same, and means for variably extending the side walls of said compartment forwardly.

3. In a news stand, means including side wall elements for forming a compartment with an opening at its front, a cover for said opening, means for swingably supporting said cover in one position, means for slidably supporting said cover in another position wherein it extends horizontally above and beyond said opening to shield said opening at the top, one of said elements at each side being extensible to shield said opening at the sides.

4. In a news stand, means forming a dispensing compartment having opposite sides and an opening at its front, a cover for said opening, means for hingedly supporting said cover at the upper edge of said opening, said

means being disengageable when the cover is swung upwardly thereabout to an approximately horizontal position, means for slidably receiving the cover when it is moved to said approximately horizontal position, said cover being greater in length than the depth of said compartment so that it will in all horizontally-supported positions afford a substantial shelter above and beyond said opening.

5. In a structure of the character described, a plurality of walls forming a compartment open at its front, another wall adjustable along the top of said compartment and down in front of and over said opening, and side walls which are slidably connected at a plurality of points to the respective sides of said compartment for free adjustment of said wall inwardly and outwardly along the sides of said compartment.

6. In a structure of the character described, a plurality of walls forming a compartment open at its front, another wall adjustable along the top of said compartment and down in front of and over said opening, side walls which are slidably adjustable inwardly and outwardly along the sides of said compartment, and a bottom having a wall associated therewith which is adjustable inwardly and outwardly to vary the size of said bottom surface.

7. In a structure of the character described, a plurality of walls forming a compartment having an opening for access thereto, a plurality of shelves in said compartment of lesser depth than said compartment, a wall member adjustable inwardly and outwardly in horizontal condition at the top of said compartment and for swing movement for opening and closing said opening, said compartment-forming walls being also extended upwardly providing a space above said adjustable wall, said space being accessible through the opening of said compartment when said adjustable wall is adjusted to at least one horizontal position, and a shelf in said space.

8. In a structure of the character described, a plurality of walls forming a compartment having an opening at one side, a plurality of shelves in said compartment accessible through said opening, a wall adjustable inwardly and outwardly at the top of said compartment for closing said opening, said walls also providing a space above said slidable top wall, and a shelf in said space, said compartment shelves adjacent said latter shelf being spaced apart from one vertical wall of the compartment providing a space whereby access may be had to said latter shelf said latter shelf being concealed when said top wall is moved fully inward and accessible when it is moved outward toward the front of said compartment.

9. In a news stand, side and rear walls

forming a compartment with an open side, a hinge element adjacent the top of said open side, horizontal guideways leading inwardly from said hinge element, a cover for said open side carried normally by said hinge element and releasable therefrom to engage and move along said guideways when it is raised to a substantially horizontal position, and side wall members having parts slidably interlocked with said side walls for extension of said members in edgewise condition parallel with said side walls.

10. In a news stand, a compartmental structure having an opening and opposite side walls extensibly supported, and a front wall swingable in one position up and down and movable horizontally inward in another position to provide a variably extensible top wall, and means for locking the front wall in its down position.

11. In a structure of the character described, means for forming upper and lower compartments with common side and rear walls and each having an opening at its front, a cover for each opening, the cover for one opening of one compartment serving as an extensible bottom for the other compartment, a hinge element adjacent the upper edge of each opening, each said cover having an edge portion engageable normally with said respective hinge element for swinging movements thereof but disengageable from said respective element when the cover is moved to a substantially horizontal position, and horizontal groove devices associated with said hinge elements to slidably receive the respective cover when it is moved to a substantially horizontal position and then moved inwardly, said groove devices being adapted to support said covers in various projected horizontal positions over said openings.

12. In a structure of the character described, means for forming upper and lower compartments each having an opening at its front, a cover for each opening, a hinge rod extending across the upper edge of each opening, each said cover having a curved upper edge with an open side engageable normally with said respective hinge rod for swinging movements thereof, but disengageable with said respective element when the cover is moved to a substantially horizontal position, and horizontal groove devices extending inwardly from the upper edge of said opening and associated with said hinge rod to slidably receive the respective cover when it is moved to a substantially horizontal position and then moved inwardly to disengage said cover and hinge rod, said groove devices being adapted to support said covers in various projected horizontal positions over said openings.

13. In a structure of the character described, side, rear, top and bottom walls

- forming a compartment open at the front, a partition member, an extensible cover associated with said partition member, extensible side members associated with said side walls, another extensible cover at the top of said compartment, and means for supporting both said covers rendering them swingable to close the sections of the compartment as defined by said partition members.
14. In a structure of the character described, side, rear, top and bottom walls, an intermediate horizontal wall carried by said side walls forming upper and lower compartments, each open at the front, an extensible intermediate wall associated with said first intermediate wall, extensible side walls, and a horizontally adjustable cover, and means for supporting said cover rendering it swingable to cover the front of said upper compartment, and means supporting said intermediate extensible wall rendering it swingable to cover the front of said lower compartment.
15. In a structure of the character described, a rear wall, outer side walls, inner side walls spaced from the respective outer side walls, side panels slidably supported between said inner and outer walls, and means for slidably supporting said panels including elongated openings in one of said side walls at each side and projections on said panels received in said openings.
16. In a news stand, a rear wall, outer side walls, inner walls spaced from the outer side walls, extensible side walls between said outer and inner side walls, all said walls being formed of sheet metal, said inner side walls having horizontal flanges struck out on their inner surfaces, a shelf supported by said flanges, said extensible side walls having a part struck out therefrom and projecting into the opening in the inner side wall formed by striking said flanges therefrom so that it is slidably interlocked with said inner side wall.
17. In a structure of the character described, means for forming a compartment including side walls, extensible side walls associated with said first side walls, horizontal slots in said first side walls, and projections on said extensible side walls adapted to project into said slots and slidably interlock said extensible and other side walls together.
18. In a structure of the character described, means for forming a compartment having an opening at one side including spaced side walls, a cover for said opening, means adjacent the upper edge of said opening for hingedly supporting said cover, the corresponding side walls at the opposite sides of said opening forming, in part, the inner wall of said compartment being extended horizontally outward then upward and inward at their upper edges providing horizontal guideways adapted to slidably receive the adjacent side edges of said cover to support the cover in various horizontal positions above said opening.
19. In a structure of the character described, means for forming a compartment having an opening at the front including spaced inner and outer walls at each side, horizontal guideways between the top edges of said inner walls and said outer walls, means normally supporting said cover for hinging movement but permitting disengagement of the cover when it is swung to a substantially horizontal position and moved inwardly, said means being located adjacent said guideways whereby said cover will enter said guideways when moved inwardly and will be supported in horizontal position thereby, and slidable walls supported between said outer and inner side walls and having parts slidably associated with said inner side walls.
20. In a structure of the character described, means for forming a compartment including rear and front and outer side walls each having its top edge extended horizontally and then vertically to provide an overhanging edge surface, a top having its edges turned downwardly vertically with its vertical part secured directly to the vertically extended part of the respective walls to provide a roof structure extending beyond the said rear, side and front wall surfaces.
21. In a structure of the character described, rear, side, and front walls defining an outer shape and surface, each said wall having its top edge extended horizontally and then vertically to provide an overhanging edge surface, a top having its edges turned downwardly vertically and secured to the vertical part of the respective wall to provide a roof structure extending beyond the said rear, side and front wall surfaces, the bottom edges of said walls being also extended horizontally to provide a solid support.
